UNITED STATES PATENT OFFICE.

EDWARD POPLAWSKI, OF NEW KENSINGTON, PENNSYLVANIA.

IRONING-BOARD.

1,201,867.

Specification of Letters Patent.

Patented Oct. 17, 1916.

Application filed February 2, 1916. Serial No. 75,836.

To all whom it may concern:

Be it known that I, EDWARD POPLAWSKI, a citizen of the United States, residing at New Kensington, in the county of Westmoreland and State of Pennsylvania, have invented new and useful Improvements in Ironing-Boards, of which the following is a specification.

The present invention contemplates the provision of a combined ironing board and step ladder, the object being to provide a structure capable of being readily and easily converted into either one of the above mentioned devices, and the parts being adapted to fold in flat condition when not in use, so that the device as a whole will occupy a minimum amount of space.

Other objects will appear as the nature of the invention is better understood, the same residing in the construction, combination and arrangement of parts hereinafter more fully described and claimed.

In the drawings forming part of this application like numerals of reference indicate similar parts in the several views and wherein:

Figure 1 is a side elevation showing the position of parts when the device is used in the capacity of an ironing board. Fig. 2 is a longitudinal sectional view therethrough showing one end of the board in elevated position. Fig. 3 is a view showing the parts in folded position. Fig. 4 is a bottom plan view of the device folded. Fig. 5 is a view showing the position of parts when the device is used in the capacity of a step ladder.

Referring more particularly to the drawings A indicates the ironing board of the usual formation, and B the step ladder comprising the spaced parallel side members 5 and the rungs 6. Secured to the under side of the board A adjacent the small end thereof are spaced transverse cleats 7 and 8 respectively adapted to be arranged at the opposite sides of the uppermost rung of the ladder, in spaced relation thereto, to permit a pivotal movement of the board, the latter being held operatively associated with the ladder by means of a pivoted latch 9 secured to the cleat 7 and adapted to bridge said rung as shown. The opposite end of the board is supported by means of the vertical end support C, which latter comprises the spaced parallel members 10 connected by means of the cross bars 11, the

end support being mounted for pivotal movement between the parallel members 14 terminally connected to the opposite ends of the intermediate cross bar 11, while the opposite ends of the members 14 are pivotally connected with the cross bar 15 which connects the upper ends of the supporting legs 16 pivotally mounted on the outer side of the side members 5 of the ladder. The lowermost rod 11 of the end support projects beyond the parallel members thereof and are arranged within the slotted guide members 17 secured to the side members 5 of the ladder and longitudinally disposed with relation thereto, whereby the end support is guided in its movement to both folded and extended position in the manner to be presently described.

18 indicates the shelf board of the ladder, the side members 19 of which extend a considerable distance beyond the edge of the board proper and are pivotally connected to the side members 5 adjacent the upper end thereof. When the device is used in the capacity of an ironing board, the shelf board 18 is swung to a position beneath the ladder and into engagement with the supporting legs 16, thereby effectively bracing the legs against casual movement, with a view of rigidly supporting the board proper in position for use. Carried by the forward edge of the shelf 18 is a pivoted hook 20 adapted to engage within an eye 21 carried by one of the rungs of the ladder to hold the shelf board in operative position hereinabove described.

It will be noted that the parallel members 10 of the vertical end support are not directly connected with the board A, the latter being merely intended to rest upon the upper ends of the parallel members, but for the purpose of pivotally connecting the large end of the board that projects beyond the end support with the parallel members 10, I employ what may be termed a yoke member consisting of the spaced parallel members 23 which are connected by means of the cross bars 24, one of which is journaled between the apertured lugs 25 secured to the under side of the board, while the opposite ends of the parallel members 23 are pivotally mounted upon the uppermost cross rod which serves to connect the parallel members 10.

In the position of parts shown in Fig. 1 when the device is set up in position for

use in the capacity of an ironing board, the yoke member is angularly disposed with relation to the parallel members 10 and assists the vertical end supporting member in supporting the board in the position shown. It will be noted that by reason of the pivotal connection between the board and the yoke members 23, the small end of the board may be detached from the ladder by releasing the pivoted latch 9, and elevated in the manner shown in Fig. 2 to permit a skirt or like garment to be slipped over one end of the board, and the small end of the board subsequently locked in position by means of the latch 9.

Now when use of the board is not desired the various elements hereinabove described in connection with the ladder which forms an under support for the board are capable of being folded in a flat condition so that the device in its entirety will occupy a minimum amount of space in a closet or any other place wherein the board is kept. The folding operation is performed by first releasing the shelf board 18 from under the ladder and swinging the same upon its pivot to a position above the board A. The supporting legs 16 are then swung upon their pivot in a direction toward the lower end 30 of the ladder during which operation the parallel members 10 of the end support move upon their pivot in unison and are drawn inwardly through the medium of the connecting members 14 in a direction opposite the direction of movement of the legs 16 to a folded position between the connecting members 14 and adapted to lie flat upon the ladder. During this movement the yoke member 23 is extended into alinement with the parallel members 10, and the board A lowered to assume a flat condition with respect to the ladder. The rest board 18 is then swung to the position initially occupied by the same beneath the ladder and the hook 20 engaged within the eye 21 for holding the rest board against swinging movement. By reason of the fact that the parallel members 10 of the end support are arranged between the guide members 17 and spaced therefrom for the purpose of folding to a position in parallel relation thereto, the lowermost cross rod 11 of the end support has secured thereto the collars 25' which engage the guide members 17 to prevent lateral movement of the end support while being moved to either extended or folded position thereby facilitating this operation. It will be noted that the compact arrangement of parts produces a comparatively small article so that the device will occupy a minimum amount of space when not in use.

When the device is desired for use in the capacity of a step ladder, the rest board 18 is first swung to a position in advance of the board 5, and the supporting legs 16

swung in the direction of the upper end of the ladder and adapted to lie at the opposite sides of the members 5 in parallel relation thereto. During this movement of the legs the parallel members 10 of the vertical end support together with the yoke members 23 are extended in alined relation, thereby spacing the board A from the ladder proper the required distance to rigidly support the ladder in upright position as clearly shown in Fig. 5. The upper ends of the parallel members 10 are grooved to receive the lowermost cross bar 24 of the yoke member when the device is used in this capacity to hold the parallel members 10 and yoke members 23 rigid in extended position. The device may be readily and easily folded from the position shown in Fig. 5, by swinging the legs 15 upon their pivot in the direction of the large end of the ladder, whereupon the various parts of the device will move in unison to folded position in the manner hereinabove described.

It will be manifest from the foregoing description that I have devised a very convenient article in the nature of a combined ironing board and ladder wherein the structure permits of a quick manipulation to convert the device into either one of the above mentioned articles when use of such article is desired.

It is believed that from the foregoing description the nature and advantages of the invention will be thoroughly understood without requiring a more extended explanation and therefore the same has been omitted. However I do not limit myself to the precise construction and arrangement of parts illustrated, and desire to have it understood that various changes in this respect may be resorted to when desired as fall within the scope of the appended claims.

What is claimed is:—

1. A device of the class described comprising in combination with a board, a ladder pivotally associated with one end thereof, supporting legs pivotally secured to the side members of the ladder, a vertical end support at the opposite end of the board, a pivotal connection between said legs and end support, a pivoted shelf board for the ladder, said shelf board being adapted to be swung beneath said ladder into engagement with said legs to brace the latter, and means for holding said shelf board in position beneath the ladder.

2. A device of the class described comprising in combination with a board, a step ladder pivotally associated with one end thereof, guide members secured to the side members of the ladder, a vertical end support comprising spaced parallel members, a cross rod connecting said members and having its ends arranged within said guides, supporting legs pivotally secured to the said side

members of the ladder, and members pivotally connecting said end support and legs whereby the former with said board is moved within said guide to folded position 5 upon the ladder in unison with the folding of said legs.

3. A device of the class described in combination with a board, a step ladder pivotally and detachably associated with one end 10 of the board, a vertical end support for the opposite end of said board, supporting legs pivotally secured to the side members of said ladder, a member pivotally connecting said end support and legs, a yoke member piv-

otally connecting said end support with the 15 adjacent end of the board, and said yoke being disposed angularly with relation to said end support when said legs are in active position, and adapted to be swung in alignment therewith upon movement of said legs 20 to a position in parallelism with said ladder.

In testimony whereof I affix my signature in presence of two witnesses.

EDWARD POPLAWSKI.
